METHOD OF MODULATING HIGH FREQUENCY TRANSMITTERS

Ernst Kramar, Berlin-Tempelhof, and Erich Heinecke, Berlin-Lichtenrade, Germany, assignors to C. Lorenz Aktiengesellschaft, Berlin-Tempelhof, Germany

Application August 21, 1935, Serial No. 37,122
In Germany February 5, 1935

4 Claims. (Cl. 179—171)

In various cases, such as with sound modulated transmitters for feeding radio beacons, the problem arises of keeping the degree of modulation constant. Let first the problem be briefly explained which exists for instance with radio beacons. It has been proposed with a radio beacon for ultra short waves to feed a dipole continuously from the transmitter and to key two reflector dipoles alternately in the dot-and-dash rhythm. This beacon arrangement if erected at a suitable place may be used not only for lateral direction finding but also for landing according to the slip-way method. However, the application of the slip-way method which as is well known works with an intensity indication, the descent being along a curve of constant field intensity requires that on the receiving side the loudness be not subject to variations. Since the loudness for a constant amplitude of the modulation frequency depends on the modulation degree the problem here is to keep constant the amplitude of the frequency which is to be modulated. In order, moreover, to obtain a large range of transmission, while ensuring that the transmitter be well utilized, the transmitter is modulated very intensely, namely to a degree beyond 90%.

It is relatively simple to maintain the constancy of a modulation frequency employed for characterizing the beacon, such as a frequency of say 1000 C. P. S. The amplitude of the carrier frequency however is less easy to maintain constant. If now for instance the amplitude of the carrier frequency decreases while the modulation frequency continues to be of a constant amplitude, then an overmodulation occurs because as stated a very intense modulation is provided for. Although in this way the transmitter will not in any case be fully overmodulated yet at least harmonics or over-tones will occur, which interfere very seriously with the navigation. As is well known, in addition to the main beacon so-called pre-signals are employed with radio beacons, such pre-signals being based for instance on the same wavelength while working with different characteristic tones. These pre-signals serve for example to characterize the commencement of the landing or serve to indicate the boundary of the landing ground. If now harmonic waves arise due to overmodulation of the beacon transmitter then there is the danger that these indicating devices for the other signals, such as the said pre-signals, are caused to respond, which should of course be avoided.

According to the invention the problem of

maintaining the modulation degree constant is solved by controlling either the bias of a stage connected in advance of the modulation stage or the bias of the modulation stage itself.

Two embodiments of the invention are shown by way of example in the accompanying drawings,

Fig. 1 being a diagrammatic representation of one of these embodiments,

Fig. 2 is a diagrammatic representation of the other embodiment.

In Fig. 1 the first three stages I, II, III of a multistage transmitter are shown.

The first stage I is arranged to operate with quartz control; in the second stage II a control for effecting the constancy of the modulation degree is active, while in the grid circuit of the third stage III the modulation is effected. The modulation frequency is impressed over the transformer T upon the push-pull tubes R_{III} by grid voltage modulation. In the anode circuit an inductance L₁ is connected which is located in the grid circuit of the next stage. Further, through the inductance L₂ a rectifier G, which in the case represented is a tube the grid of which is connected to the anode, is coupled. The rectified voltage is used for controlling the grid bias of the second stage over a condenser C_g and a choke D_g. The control is effected with the aid of the resistance V and W. Included in series with V is a choke D_{II}. At -G_v a constant negative bias is given. The other parts represented in the drawings are well known. They have per se nothing to do with the invention.

The mode of action of the arrangement is as follows: The modulation frequency arriving over T is practically constant. The carrier frequency already modulated is rectified in the output circuit of the third stage by the rectifier G. The resultant continuous voltage is a means for measuring the magnitude of the carrier, for as is well known the mean value of a modulated oscillation does not vary if the transmitter is otherwise constant. The voltage relations are now so selected that the grid bias of the stage II shall always be so controlled that the carrier amplified in stage II shall always be of the same magnitude. The only requirement is that the control is effected in a stage in which the magnitude of the carrier alone can be influenced, as otherwise the mentioned phenomena of over-modulation cannot be avoided.

Instead of the rectifier tube here employed rectifiers of other kind, such as oxide rectifiers, may of course be used. Furthermore the con-

trol may of course be effected in another manner customary in the high frequency art.

The further invention, to which Fig. 2 relates, proposes to rectify part of the non-modulated carrier frequency and to use the resultant continuous voltage for controlling the bias of one of the prestages of the transmitter. In order to effect this method, preferably a tube rectifier is employed whose control grid is attached to the high frequency potential of the anode whilst this control grid is at the same time given a continuous current bias.

This will be understood from the following description which also states the advantages due to rectifying the non-modulated carrier frequency.

In Fig. 2 four stages of a multistage transmitter are shown. The stage I operates with quartz control. In the stage II a control for effecting the constancy of the modulation degree is active, whilst in the grid circuit of the stage IV the modulation is accomplished. In the output circuit of the stage III the continuous control voltage is derived by the rectifier G. The modulation frequency is impressed over the transformer T upon the push-pull tubes R₁ and R₂ by grid voltage modulation. The rectifier G is coupled through a condenser C. The continuous voltage which the rectifier G produces at the resistance W across the choke D₁ is led, for instance through a resistance V and a choke D₃, to the grid of the tube of stage II. The grid of the rectifier tube is caused by the condenser K to have the same high frequency potential as has the anode, and hence is short-circuited with respect to the high frequency. Over the choke D₂ a constant continuous voltage is given to the grid of the rectifier. If in the usual manner the grid were connected directly with the anode then the grid bias of the stage II, i. e. the grid bias having to be regulated in order to ensure a reliable operation of the transmitter, and the setting or adjusting of the rectifier working point, would not be independent of each other. This is avoided by the provision that the grid of the rectifier is caused by condenser K to have the high frequency potential of the anode, while over the choke D₂ continuous voltage is available for enabling the rectifier working point to be set at will, so that a regulation of the stage II by the rectified carrier occurs only at a definite value, that is to say, it is this value which is kept constant. Over the

resistance W a constant continuous voltage is led to the grid of the stage II as shown.

The bias on the grid of the rectifier may be controlled continuously, such as by the modulation tone or in dependency upon the network voltage. In the first case one has to rectify the modulation tone and to employ the resultant continuous voltage for controlling the grid.

In the foregoing description referring to Fig. 1, in order to maintain the modulation degree constant, the assumption has been made that the modulation tone is in itself of constant amplitude, this being in many cases obtainable by simple means. If such is not the case however, then for rendering the loudness in the receiver constant the modulation tone may as stated be rectified and thus the bias of the rectifier be controlled. The field intensity of the transmitter, it is true, will then not be constant, but at least the modulation degree will be so, so that variations in the loudness will be prevented with the receiver adjusted for a definite sensitivity. The same method may be adopted also if variations in the network voltage occur. In this case the rectifier will be controlled in dependency upon the network voltage.

What is claimed is:

1. In a sound modulated transmitter having several high frequency stages including a modulation stage preceded by non-modulating stages and having means for rectifying a part of the output current of one of said high frequency stages, the method of keeping constant the degree of modulation which comprises applying a modulating signal of constant amplitude to the modulating stage and utilizing the direct current potential derived from said rectification to control the gain of a high frequency stage preceding that from which the direct current potential was derived.

2. A method according to claim 1, wherein the direct current potential is derived from the output of said modulation stage.

3. A method according to claim 1, wherein the direct current potential is derived from the output of the modulation stage and is filtered prior to employing said voltage for controlling the gain of a preceding high frequency stage.

4. A method according to claim 1, wherein the direct current potential is derived from the output of one of said non-modulating stages.
